MECHANICAL CANDLE FEEDER

Filed May 18, 1948

UNITED STATES PATENT OFFICE

2,480,333

MECHANICAL CANDLE FEEDER

Donald F. McClory, San Francisco, Calif.

Application May 18, 1948, Serial No. 29,537

1 Claim. (Cl. 67—27)

1

This invention relates to a mechanical candle feeder.

Among the objects of the invention is the mechanical simulation of the conventional shape and general appearance of "wax" candles.

Another object is the provision of means for controlling the volume of melting wax incidental to the wick consumption of the melting candle.

Another object is the provision of means for firmly and adjustably fixing the candle base in various sizes of candlesticks.

Other objects and advantages will appear as the description proceeds. In the specification, and the accompanying drawings the invention is disclosed in its preferred form. But it is to be understood that it is not limited to this form; because it may be embodied in modifications within the spirit of the invention as defined in the claim following the description.

In the one sheet of drawings:

Fig. 1 is a vertical section of a mechanical candle constructed in accordance with this invention.

Fig. 2 is a horizontal section of the same on the line II—II Fig. 1.

In detail the structure shown in Fig. 1, comprises the compressible clutch-plug 1, preferably composed of a resilient plastic such as neoprene resembling a rubber compound. It is interposed between the bottom and top washers 2, 3 and has the screw 4 passing through both washers and the clutch-plug 1, with the screw head 5 bearing against the bottom washer 2. The screw is threaded through the round nut 6 which bears against the top washer. The upper end of the screw is upset outwardly so that it cannot be backed out through the nut 6 from below.

The candle feed comprises the tube 7 having its lower end clinched around the nut 6. The tubular plunger 8 has the closed top 9 and the slightly flared lower edge 10, which abuts the inturned upper edge 7' of the tube in the fully extended position. The expansive spring 11 is interposed between the nut 6 and the top 9 of the plunger. The lower end portion of the tube 7 has the projecting tits 12, 13 upset in the body of the tube.

The tapered tubular case 14, simulating the outward appearance of a candle, has the inturned top portion at 15. The lower end of this tube is flanged inwardly at 16 around the annulus 17 which surrounds the circumference of the tube 7 beneath the tits 12, 13. The annulus has the opposed notches 18, 19, to pass these tits, forming in effect a bayonet connection between the tube 7 and the case 14. The lug 20 is bent in-

2

ward from the annulus into the path of the tits 12, 13 to limit the turning of the case 14 relative to the tube 7, for locking this bayonet joint.

This invention operates substantially as follows: The clutch-plug 1 is grasped by one hand while the tube 7 is held in the other hand. The clutch-plug is then turned until it is an easy fit within the socket 21 in the holder 22, which functions as a "candle stick." The tube 7 is then rotated on the screw 4, which compresses the clutch-plug 1 until it is expanded within the socket 21 to hold the tube 7 firmly upright in the candle stick, such as 22.

The candle 23 is then inserted into the case 14 through the annulus 17. The case is then lowered over the tube 7, until the candle depresses the plunger 8 and enters the upper end of this tube, against the expansion of the spring 11, which forces the wick end of the candle upward until the wick 24 is exposed above the inturned upper end 15 of the case 14. The case is then rotated until the tits 12, 13 pass through the notches 16, 17 and one of the tits contacts the stop lug 18. This holds the apparatus in firm assembly in the holder 19.

When the wick 24 is lighted the heat melts the upper end of the candle and the resultant fluid wax is impounded within the upper end of the case at 25, the inturned end 15 forming a pool of fluid wax to feed the burning wick. The candle is gradually consumed and forced upwardly by the constant expansion of the spring 11. The incidental heat of combustion is absorbed and radiated by the enclosing case 14, and protects the body of the candle against excessive disintegration, and dripping downward. As the body of the candle is consumed at the puddle 25, it is pushed upward progressively until the top of the plunger 8 seals against the inturned flange at the top 15 of the case. In this manner the whole of the candle 20 is consumed, without waste and without dripping downward.

In many antique candelabra, especially Chinese, the sockets are irregular in diameter, taper and general formation. The expansive clutch-plug 1 is easily locked within such sockets and the several candles may be maintained in proper alignment with each other.

The resiliency and high frictional efficiency of the clutch-plug 1, enables it to adjust itself to out-of-round and tapered sockets in candle sticks and maintain its vertical adjustment.

Having fully described this invention and its mode of operation, what I claim and desire to secure by Letters Patent is:

A mechanical candle feeder comprising a tube having a restricted upper end and its lower end closed by a nut fixed therein; a tubular plunger with a closed upper end and slideable within said tube and extending above the said restricted upper end of said tube and having a flared lower end engaging beneath said restricted upper end of said tube; an expansive spring telescoping within said tube and plunger between said nut and the closed upper end of said plunger; a tubular outer case telescoping over said tube and having a restricted upper end and detachably attached to said tube adjacent said nut; a candle interposed between the closed end of said plunger and a restricted upper end of said case; a screw threaded in said nut; and a cylindrical rubber-like clutch plug interposed between the head of said screw and said nut and adapted to be ex-

panded by compression when said nut is turned relative to said screw and be frictionally anchored in the socket of a candle supporting base.
